UNITED STATES PATENT OFFICE.

PHILIP EMRICH, OF CINCINNATI, OHIO.

ADJUSTABLE ROOFING-TONGS.

No. 873,358.

Specification of Letters Patent.

Patented Dec. 10, 1907.

Application filed May 17, 1906. Serial No. 317,330.

To all whom it may concern:

Be it known that I, PHILIP EMRICH, a citizen of the United States, residing at Cincinnati, in the county of Hamilton and State of Ohio, have invented certain new and useful Improvements in Adjustable Roofing-Tongs, of which the following is a specification.

My invention relates to means for adjusting the tongs to produce varying sizes of 10 seams.

The object of my invention is to provide roofing tongs which are adapted to be easily and conveniently adjusted whereby a single pair of tongs may take the place of several 15 tongs of different sizes and whereby the adjustments may be made to produce any width of seam desired.

My invention consists in providing roofing tongs with an adjustable gage at each end to 20 limit the extent of metal to form the seam which may be inserted between the jaws of the tongs and to be readily moved to vary the width of said seam to any desired distance.

25 My invention also consists in the parts and in the construction, combination and arrangement of parts as set forth and claimed.

In the drawings which serve to illustrate my invention: Figure 1 is a perspective view 30 of the gage. Fig. 2 is a rear view showing the flange. Fig. 3 is a side view of a pair of roofing tongs embodying my invention. Fig. 4 is a rear view of one of the jaws showing means for fastening the gage thereto.

35 Fig. 5 shows a modified form of my invention. Fig. 6 shows a modification in which the scale is placed upon one of the jaws. Fig. 7 is an end view of the device when closed. Fig. 8 is a similar view when open. Fig. 9 40 is another modification showing the scale on the jaw upon which the gage is mounted.

My invention is preferably constructed substantially as follows: The jaws 1 and 2 of the tongs are constructed in the ordinary 45 manner with bevel edges 3 and 4 respectively to more readily grasp the work except that the jaw 1 is cut away at each end to make it shorter where cut away than the corresponding part of the opposing jaw 2 as in 50 Fig. 3 which shows each end of jaw 1 entirely cut away or as in Fig. 5 which shows each end of jaw 1 partly cut away the beveled edge 3 being retained to oppose the corresponding beveled edge 4 of jaw 2 when the 55 same are brought to bear upon the work. The parts cut away at each end of jaw 1

leave a space 5 at one end and a space 6 at the other end thereof to receive adjustable gages 7 and 8 respectively. Each adjustable gage is formed in the shape shown in Fig. 1 60 with a body 9 having a longitudinal slot 10 therein to receive a bolt and permit of lengthwise adjustment of said gage, a channel 11 adjacent said slot adapted to receive a nut and hold it from turning, a stop 12 to limit 65 the distance which the work to be operated upon may be inserted between said jaws and also prevent it from passing too far when said jaws are open and a flange 13 to prevent said work from passing between said adjustable gage and jaw 2 and to assist in holding said gage more firmly in adjusted position.

A scale 14 is provided upon each gage or upon one of the jaws adjacent to said gage to 75 enable each gage to be adjusted and set alike to measure any width of seam desired from the smallest part of an inch up to the full limit of the gage. Each gage is secured in adjusted position as shown in Figs. 3, 4 80 and 5 by means of a screw bolt 15 taking through a bolt hole 16 in jaw 2 and longitudinal slot 10 in said gage into nut 17 resting in channel 11 in said gage whereby said nut is held from turning while said screw bolt is 85 being turned in said nut to tighten or loosen the gage. The head of the screw bolt 15 is preferably counter-sunk in jaw 2 as shown by dotted lines in Fig. 7.

To hold the gage firmly and securely in 90 fixed position simply turn the screw bolt by means of a screw driver until the nut has been drawn tightly against the gage. The wear upon the gage is very slight and of such a nature as not to affect its accuracy or efficiency, since any wear is taken up by the nut and screw bolt in the successive adjustments.

Some of the advantages of my construction are its economy in cost of manufacture and its extreme simplicity and convenience 100 in adjusting to set it for any particular size of seam desired, down to a small part of an inch.

A desirable feature of my invention consists in the rapidity with which the gages may be reset or adjusted to make a different 105 width of seam.

By having the tongs constructed as described with my adjustable gages applied thereto the same are adapted to take the place of eight or more similar tongs when 110 constructed with non-adjustable gages and the manner of constructing and applying

my adjustable gages renders the tongs extremely light, which is an important feature since they should not be any heavier than is necessary to accomplish the work desired in order that they may be conveniently carried and handled by the operator. It will be seen that a great saving will result to the user by being required to purchase only one pair of tongs in place of eight or more, and a further advantage results in the operator having to carry only one pair upon roofs or elsewhere instead of a large number.

The operation of adjusting the gages is extremely simple and consists merely in turning screw bolt 15 by a screw driver first in one direction to loosen the adjustable gage and then in the reverse direction to tighten it after it has been adjusted to the desired point upon the scale.

20 To obtain any desired width of seam move the gage lengthwise, as, for instance, to obtain a one-half inch seam adjust the gage lengthwise until the gage mark *x* on the jaw 1 is opposite the half inch mark on the scale 25 as shown in Fig. 3. To set the gage when the scale is upon the jaw merely adjust the outer edge of the stop 12 opposite the point upon the scale which indicates the width of seam desired, as for instance, a three-fourth 30 inch seam is indicated by the position of the gage in Figs. 6 and 9. After the gage has been set for the required width of seam the operator takes the tongs by the levers 18 and 19 and opens the jaws from the position 35 shown in Fig. 7 to the position shown in Fig. 8 and slides the jaws over the edge of a piece of tin or sheet metal to be operated upon until it comes into contact with the stop 12 when the jaws are closed and the levers 40 brought to an upright position or at right angles to the surface upon which the metal is resting. This produces the necessary bend in the metal and such as is contemplated by the use of this tool.

45 I claim:

1. In adjustable roofing tongs, a pair of jaws one of which projects beyond the other at each end, an adjustable gage at each end of the shorter jaw, means for securing each 50 gage to the longer jaw to hold it in an adjusted position thereon, and a scale on each adjustable gage by which to set said gages and measure the width of seam, substantially as set forth.

55 2. In adjustable roofing tongs, a pair of jaws one of which projects beyond the other at each end, an adjustable gage upon the pro-

jecting parts of the longer jaw at each end of the shorter jaw, means for adjusting the gage to hold it in adjusted position upon the longer jaw and adjacent the ends of the shorter jaw, a scale upon each gage, and a gage mark upon the shorter jaw adapted to register with the respective graduations of the scale, substantially as set forth. 65

3. In adjustable roofing tongs, a pair of jaws one of which is cut away at each end, an adjustable gage at each end of said cut away jaw, means for adjusting each gage to hold it in adjusted position upon the jaw which is 70 not cut away and a flange upon said gage adapted to take over and bear against the jaw which is not cut away.

4. In adjustable roofing tongs, a jaw cut away at each end, an opposing jaw, an adjustable gage secured to the opposing jaw at each end within the space cut away, said gage having a slot, a screw bolt taking through a hole in said opposing jaw and through said slot, a nut adapted to engage 80 said screw bolt, means upon said gage adapted to engage said nut whereby it is held from turning and a stop to limit the extent of insertion of the metal between said jaws. 75

5. In adjustable roofing tongs, a jaw cut away at each end, an opposing jaw, an adjustable gage adapted to occupy the cut away space at each end and rest against the end of said cut away jaw and the inner surface of the opposing jaw, said adjustable 90 gage having a slot, means for securing said gage to said opposing jaw and a flange upon said gage adapted to extend over the end of said opposing jaw whereby the metal plate operated upon is prevented from passing 95 between said jaw and gage and whereby said gage is more firmly held in adjusted position.

6. In adjustable roofing tongs, a jaw cut away at each end, an opposing jaw extending opposite parts cut away, an adjustable gage 100 adapted to take into the space cut away and bear against the end of the cut away jaw and the inner surface of the opposing jaw, a screw bolt secured to said opposing jaw adapted to pass through a longitudinal slot 105 in the adjustable gage, a nut secured to said bolt adapted to rest within a channel in said nut to hold it from turning and a scale upon one side of the gage adapted to measure the width of seam desired.

PHILIP EMRICH.
